UNITED STATES PATENT OFFICE.

FRANK EDWARD SMITH, OF NEW ORLEANS, LOUISIANA.

AUTOMATIC FLUSH-VALVE.

SPECIFICATION forming part of Letters Patent No. 627,357, dated June 20, 1899.

Application filed February 17, 1899. Serial No. 705,918. (No model.)

To all whom it may concern:

Be it known that I, FRANK EDWARD SMITH, a citizen of the United States, residing at New Orleans, in the parish of Orleans and State of Louisiana, have invented certain new and useful Improvements in Automatic Flush-Valves; and I do hereby declare the following to be a full, clear, and exact description of the invention, such as will enable others skilled in the art to which it appertains to make and use the same.

My invention relates to an improvement in an automatic flush-valve, and its novelty will be fully understood from the following description and claim when taken in connection with the annexed drawings; and the objects of my invention are to provide a new and useful device for flushing bowls of a water-closet and at the same time produce a device whereby the valves are not subject to the wear and tear of sediment from muddy water, such as the Missouri or Mississippi river waters. I attain these objects by the mechanism illustrated in the accompanying drawings, in which—

Figure 1 is a horizontal section of water-cylinder on the line 1 1 of Fig. 3. Fig. 2 is an end view of water-cylinder, on a smaller scale, showing bowl attached. Fig. 3 is a vertical section of the water-cylinder on the same scale as Fig. 1, the section views on the line 3 3 of Fig. 1.

Similar numerals refer to similar parts throughout the several views.

In the drawings, 1 designates a water-cylinder suitably attached in any position desired.

2 shows an inlet-pipe for supplying cylinder with water.

3 shows a flush-pipe through which water is discharged into bowl 17.

4 designates a valve-stem provided with rubber plug-valves 5 and 5^a, which open and close port 6. Placed on stem 4 is a flange 7, as shown in Figs. 1 and 3.

8 is a leather cup-shaped washer for controlling the movement of the piston.

9 designates an arm engaging the stem 4, said arm being fast to the rock-shaft 9^a, carrying the lever 10, provided with a chain 14, attached to the seat 15.

11 shows a spring bearing on the piston.

12 is a water-port closed and opened by valve 13.

16 is a hinge which is attached to seat 15 and 55 to a lug on the bowl 17.

18 represents the waste-pipe for bowl.

19 shows a valve controlling the flow of water from the supply-pipe 20.

21 shows a base or floor. 60

The operation of my device is as follows: The seat of the closet being occupied, the chain 14 is raised and the rock-shaft 9^a partly rotated, operating the arm 9 and valve-stein 4 forward, thus moving the valve 5 from its seat and causing the valve 5^a to close the port 6. During the time when the valve 5 leaves the port until the time the valve 5^a closes the same a flow of water will pass through the port 6 from the inlet-pipe and pass through 70 the port and out through the outlet-pipe into the bowl of the closet. This small flow of water wets the bowl and prevents the adherence of matter to its sides. When the pressure is removed from the seat, the valve 5^a is 75 pushed back from its seat by the action of the spring 11, and the water flows through the port 6 and into the bowl of the closet until the port is closed by the valve 5. The volume of water to flush the bowl is regulated 80 by the speed with which the valve 5 moves to close the port 6. This speed is regulated by means of the cup-shaped piston 8. As soon as the seat is pressed down and the valve-stein moved to the right, Fig. 3, water passes 85 through the passage 12 into that part of the chamber 1 inclosed between the end of the cylinder and the cup-shaped piston. When the pressure is removed from the seat, the action of the spring 11 is controlled by the 90 water-cushion formed behind the piston. Thus it will be seen that if the valve 13 were shut the flow of water to flush the bowl of the closet could be made constant.

An advantage of my invention is its economical construction and the ease by which it may be operated and repaired should it be necessary. It dispenses with complicated and unsightly tanks, piping, and weights, the seat being one of the levers used and that being of the simplest form. It is impossible for sand or sediment to accumulate in any part of the valve, and the result is attained without delicate or complex mechanism of any

kind and with no stuffing-boxes standing under pressure, the valve being so small as to be completely hidden by the bowl and seat. This valve feeds a direct pressure which is 5 always greater than any flush attained by a flush-tank, and consequently uses less water. The volume pressure and length of time flush discharges is under perfect control on the outside. This closet can be installed with a 10 small amount of labor and with no damage to walls. It is simple, durable, and economical.

Having thus described my invention and the manner in which the same is or may be 15 carried into operation, I would say in conclusion that I do not limit myself to the precise details shown in illustration, as the same may be varied to some extent; but

What I claim, and desire to secure by Letters Patent, is—

The herein-described flush-valve consisting of a cylindrical chamber, provided with inlet and outlet pipes, a valve-seat formed integral

with and dividing said chamber into two compartments, a valve-stem passing through the 25 port of said valve-seat and provided with plug-valves operating in unison to open or close said port, a flange mounted on one end of said valve-stem, a spring within said chamber pressing against said flange, a cup-shaped 30 piston mounted on the other end of said valve-stem, a water-duct opening into said chamber behind said piston, and a valve on the outside of said chamber for controlling the passage of water through said duct; in combination 35 with a closet-bowl, a seat hinged to said bowl and provided with a chain connected to a lever attached to said valve-stem for operating same, substantially as described.

In testimony whereof I affix my signature 40 in presence of two witnesses.

FRANK EDWARD SMITH.
